UNITED STATES PATENT OFFICE.

BERNARD JACQUART, OF SOUTH RIVER, NEW JERSEY.

DESIGN FOR A BRICK OR TILE.

SPECIFICATION forming part of Design No. 34,284, dated March 26, 1901.

Application filed February 26, 1901. Serial No. 49,004. Term of patent 14 years.

To all whom it may concern:

Be it known that I, BERNARD JACQUART, a citizen of the United States, and a resident of South River, in the county of Middlesex and State of New Jersey, have invented and produced a new and original Design for a Brick or Tile, of which the following is a specification.

The essential feature of my design consists in a brick or tile which presents a regular rectangular outline when viewed from the back, front, and either side and an irregular outline when viewed from either end, which irregular outline consists of a flat bottom line, straight side lines, rounded lines connecting the straight bottom line with the straight side lines, and an irregular top line forming a wide dovetailed groove in the brick or tile.

In the accompanying drawings, Figure 1 represents a back view of the brick or tile. Fig. 2 represents an end view of the same. Fig. 3 represents a front view, and Fig. 4 is a side view.

The brick or tile is denoted as a whole by A, and it is of such form that it presents a rectangular figure when viewed from the back, 25 front, and sides. When viewed in end elevation, the straight bottom line of the brick or tile is denoted by a, the straight sides by b c, the curved lines which form the rounded corners by d e, and the wide dovetailed groove 30 formed by the irregular top line by f.

What I claim is—

The design for a brick or tile, substantially as shown and described.

In testimony that I claim the foregoing as 35 my invention I have signed my name, in presence of two witnesses, this 8th day of February, 1901.

BERNARD JACQUART.
